UNITED STATES PATENT OFFICE.

ISAAC N. GLAUBER, OF CLEVELAND, OHIO.

DESIGN FOR A FAUCET.

SPECIFICATION forming part of Design No. 31,363, dated August 8, 1899.

Application filed June 23, 1899. Serial No. 721,641. Term of patent 14 years.

To all whom it may concern:

Be it known that I, ISAAC N. GLAUBER, a citizen of the United States, residing at Cleveland, in the county of Cuyahoga and State of Ohio, have invented and produced a new and original Design for Faucets, of which the following is a specification, reference being had to the accompanying drawings, forming part thereof.

- 10 In the accompanying drawings, forming a part of this specification and fully illustrating the invention, Figure 1 is a direct front elevation of my new and original design, and Fig. 2 is a side elevation thereof.
- 15 As thus plainly illustrated, it will be seen that the design is comprised in the faucet as a complete embodiment, but containing certain specific and novel features by which it is distinguishable and original in the art. Thus
- 20 the body or barrel 2 of the faucet is fashioned with shapely outline and a plain smooth sur-

face all around and back to its decorated inner extremity 3. Centrally upon the said barrel 2 is a pedestal 4 of cylindrical outline above the barrel and surmounted by a crown 5. Upon this crown is erected a figure resembling a cross, having a cylindrical stem 6 and equal and uniform arms 7, having cylindrical or drum-shaped portions at their base, with spherical extremities 8 and fanciful necks of varying design between said extremities and the said base portions.

What I claim is—

The design for a faucet, substantially as shown and described.

Witness my hand to the foregoing specification this 14th day of June, 1899.

ISAAC N. GLAUBER.

Witnesses:

H. T. FISHER,
R. B. MOSER.
